UNITED STATES PATENT OFFICE.

EDWIN J. DOWNING, BARTON R. SHEETS, AND LORENZO E. CROFT, OF DENVER, COLORADO, ASSIGNEES, BY MESNE ASSIGNMENTS, TO THE GARDNER-DENVER COMPANY, OF QUINCY, ILLINOIS, A CORPORATION OF DELAWARE.

ANCHOR FOR DRILL-STEEL GUIDES.

Application filed January 13, 1927. Serial No. 160,958.

The present invention relates to guides for drill steels of the type shown in the application for patent of Richard Griffith, Serial No. 146,519, filed November 11, 1926. It has been found that the anchoring means as disclosed in said Griffith application, while effective to hold the guide in place, has a wedging action so powerful that if the initial hole is close to the edge of the rock, there is a material tendency to fracture the rock and sometimes to break off the section between the hole and the side of the rock face.

The object of the present invention is to provide an anchoring means that is adjustable so that the anchoring wedge can be brought against a side wall of the opening of sufficient thickness to prevent the above difficulty.

20 In the accompanying drawings:—

Figure 1 is a side elevation of the preferred embodiment of the invention,

Figure 2 is a plan view of the same,

Figure 3 is an end elevation.

25 The body of the guide is designated 4, and is provided with a series of parallel openings 5 for the reception of the drill steel. A bushing 6 is employed that is placed in the different openings in succession as the 30 drill steel is moved from one to the other, the drill steel being shown at 7. Passing through one end of the body, is an opening 8 to receive a holding spur 9 secured in place by set screws 10.

35 In the opposite end of the body is formed a vertical guideway 11, in which is rotatably and slidably mounted an anchor rod or stem 11^a adapted to engage in the initially drilled hole 12 in the rock. This rod or stem 40 is provided with a longitudinal keyway 13, the lower end of which tapers outwardly, as shown at 14. The guideway 11 is provided in at least three of its sides with keyways 15. A wedging key 16 is adapted to 45 be slidably engaged in the keyway 13 and in any one of the keyways 15, depending on the position assumed by the anchor stem when it is rotated. The lower end of this wedging key is tapered as shown at 17, and 50 when the key is driven downwardly, it will wedge securely against the wall of the drill hole 12, thereby fastening the anchor stem in place. The outer side or edge of the wedge key 16 is provided with a series of

undercut teeth or shoulders 18 adapted to be 55 engaged by a releasing tool, and the end of the body 4 is provided in line with the keyways 15 with recessed fulcrum seats 19 on which the releasing tool or lever is adapted to rest.

With this construction, it will be evident that even though the hole 12 is partly closed to the side face of the rock, the body can be differently positioned and the anchor stem or rod can be turned so that the wedge 65 can be inserted against a portion of the rock having sufficient body to withstand the wedging action.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

What we claim is:

1. In a rock drill guide, the combination 80 with a body having a guideway for a drill steel, of means rotatably mounted in the body and engaging in a drilled hole for positioning the body with a guideway, in a predetermined position over the rock to be 85 drilled, and means mounted on and adjustable to different positions when the positioning means is rotated for securing said positioning means in different positions against rotation.

2. In a rock drill guide, the combination 90 with a body having a guideway for a drill steel, of an anchor stem rotatably mounted in the body and engaging in a drilled hole for positioning the body with the guideway in a predetermined position over the rock to be drilled, and a clamping wedge that is 95 slidably interlocked with the anchor stem and is adjustable to different positions when the stem is rotated.

3. In a rock drill guide, the combination 100 with a body having a guideway for a drill steel, of an anchor stem rotatably mounted in the body and engaging in a drilled hole for positioning the body with the guideway in a predetermined position over the rock to be drilled, and a clamping wedge that 105 engages the anchor stem and is adjustable

to different positions when the stem is rotated, said wedge having a portion adapted to be engaged by a releasing tool, and said body having different portions adapted 5 to act as fulcrums for a tool engaging said portion.

4. In a rock drill guide, the combination with a body having a guideway for a drill steel, of an anchor stem capable of sliding 10 and rotatable movement in the body, said anchor stem having a longitudinal keyway in one side, and a locking key slidable in the keyway and having shoulders for engagement by a releasing tool, and said body having different portions on different sides of 15 the anchor stem that constitute fulcrums for such tool.

5. In a rock drill guide, the combination with a body having a plurality of guideways 20 for a drill steel and having a bore at one end provided with a plurality of longitudinal keyways, of an anchor stem rotatably mounted on the bore and having a keyway that alines with the different keyways of 25 the bore, and a locking wedge slidably mounted in the keyway of the anchor stem

and adapted to engage in any of the guideways of the bore with which the keyway of the anchor stem alines.

6. In a rock drill guide, the combination 30 with a body having a plurality of guideways for a drill steel and having a bore at one end provided with a plurality of longitudinal keyways and fulcrums seats on different sides of the bore in line with the keyways, 35 of an anchor stem rotatably mounted on the bore and having a keyway that alines with the different keyways of the bore, and a locking wedge slidably mounted in the keyway of the anchor stem and adapted to engage in any of the guideways of the bore with which the keyway of the anchor stem alines, said locking wedge having teeth on 40 its outer side that are engageable by a tool fulcrumed in the seat with which the wedge 45 is alined.

In testimony whereof, we affix our signatures.

EDWIN J. DOWNING.
